US0D1078011S

(12) **United States Design Patent** (10) **Patent No.:** **US D1,078,011 S**
(45) **Date of Patent:** **** Jun. 3, 2025**

(54) **AROMA DIFFUSER**

(71) Applicant: **Shenzhen Chaojin Electronics Co., Ltd**, Guangdong (CN)

(72) Inventor: **Laihao Xie**, Guangdong (CN)

(73) Assignee: **Shenzhen Chaojin Electronics Co., Ltd**, Guangdong (CN)

(**) Term: **15 Years**

(21) Appl. No.: **29/981,544**

(22) Filed: **Dec. 31, 2024**

(30) **Foreign Application Priority Data**

Nov. 19, 2024 (CN) 202430730199.8

(51) **LOC (15) Cl.** **23-04**

(52) **U.S. Cl.**

USPC **D23/366**

(57) **CLAIM**

The ornamental design for an aroma diffuser as shown and described.

DESCRIPTION

FIG. 1 is a front, right and top perspective view of an aroma diffuser, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the aroma diffuser that form no part of the claimed design.

1 Claim, 8 Drawing Sheets
